UNITED STATES PATENT OFFICE.

JAMES FRANK DURYEA, OF SPRINGFIELD, MASSACHUSETTS.

INTERNAL-COMBUSTION ENGINE.

No. 848,887.

Specification of Letters Patent.

Patented Nov. 5, 1907.

Application filed January 19, 1907. Serial No. 363,118.

To all whom it may concern:

Be it known that I, JAMES FRANK DURYEA, a citizen of the United States of America, residing at Springfield, in the county of Hampden and State of Massachusetts, have invented new and useful Improvements in Internal-Combustion Engines, of which the following is a specification.

This invention relates to internal combustion engines and more particularly to an improvement in applicant's prior United States Letters Patent No. 798,995 dated September 5, 1905 in which the water circulating pump mechanism, described therein, is difficult to repair when leakage occurs from the same into the crank casing. In order to overcome this serious objection, I have devised the means set forth in detail in this application by which any leakage that may occur at the packing box around the circulating pump shaft may flow down on the outside of the crank-case, and also I have provided means so that when it becomes necessary to replace the packing, the same may be accomplished without disturbing the assembled parts of the engine case.

In the drawings forming part of this application, Figure 1 is a vertical longitudinal section through the commutator shaft. Fig. 2 is a detail view of my improvement showing the circulating pump and its casing removed from the engine-frame and the clutch members between the commutator-shaft and the pump-shaft separated. Fig. 3 is an end elevation of the circulating pump on the line 3-3 of Fig. 1.

Referring to the drawings, *a* designates a portion of the crank-casing; *b* designates the cam-shaft from which the valves of the inlet and outlet ports are operated and timed in the usual manner; *c* designates as a whole the commutator mounted on the end of the commutator-shaft *d*; *e* is a spiral gear carried by the commutator-shaft and meshing with a spiral gear on the cam-shaft *b* so that the shafts *b* and *d* are driven at the same speed.

f designates a portion of the engine casing that is bolted to the part *a* in the usual manner. In the side of the engine-casing *f* is formed an opening *g* for receiving the hub portion *i* of a yoke-shaped piece *h*. Within the portion *i* of the yoke-shaped piece *h* is mounted a bushing *j* having a small opening *k* to receive the tapered end of a set-screw *m* for the purpose of holding the bushing and hub portion in place in the casing. To the outer end of the yoke-shaped piece is bolted the inclosing casing *n* of the circulating pump by means of the machine-bolts *o*.

p designates a hub on the casing *n* which extends towards the engine-frame for the purpose of forming a water-tight joint between the interior of the circulating pump casing and the shaft *d*. This shaft has a clutch connection with the commutator-shaft *d*.

The exterior portion of the hub *p* is threaded for receiving the internal thread of a packing-nut *q*.

r designates a bushing located between the shaft *d* and the hub *p*. *s* also designates another bushing located between the shaft *d* and the hub *p*. These two bushings are provided with shoulder portions *t* and *t'* for engaging the correspondingly shaped shoulder portions in the inner and outer ends of the hub *p*.

u designates the ordinary packing material employed in forming a water-tight joint about a rotating or reciprocating shaft.

v designates the blades of the circulating pump located within the casing *n*. These blades are made integral with a hub portion *w* that is secured to the shaft *d*.

x designates a tubular hub portion in the outer end of the pump-casing for supporting the outer end of the shaft *d*. Located in the lower portion of the pump casing is a draw-off valve *y* for the water within the same, in order to prevent the pump freezing in cold weather.

As a result of the construction shown in this improvement, all danger of water escaping from the interior of the pump-casing into the crank-casing is avoided. Should any leakage occur past the packing *u*, it would flow outside of the crank-casing *a* without doing any harm whatever. Also this improvement permits one to readily replace the packing *u* about the shaft *d*, without dismantling the crank or engine casing in any way. This is accomplished by placing a wrench within the yoke-shaped part *h* and removing the machine-bolts *o* whereby the entire circulating pump-casing *n*, and the pump-shaft *d* may be removed from the yoke-shaped part *h*, as clearly shown in Fig. 2, thus permitting the operator to remove the packing-nut *q* and replace the packing material *u*.

The clutch construction, designated by *z*, between the shafts *d* and *d'* readily permits the coupling and uncoupling of the pump-shaft to the driving or commutator-shaft *d*.

The construction of the water-tight joint and bearing for the outer end of the shaft *d* in the portion *x* is the same as that already described in connection with the inner end of the shaft *d* and hub *p*, and does not therefore require detailed description.

The construction shown at the right-hand end of Fig. 1 forms no part of this invention, and need not be referred to in detail. It may be stated, however, that the flexible shaft 10 is adapted to run the oiler, if desired.

What I claim, is:

1. In an internal combustion engine of the class described, a base portion, a cam-shaft and commutator-shaft mounted therein and having means for driving one from the other, a yoke-shaped piece carried by the engine casing, a pump-casing removably secured thereto, a pump located therein,

110

the shaft, thereof having a clutch connection with the commutator-shaft whereby when the pump-casing is removed the pump-shaft is disengaged from the commutator-shaft.

- 5 2. In an improvement of the class described, a yoke-shaped piece secured to the engine casing, a circulating pump-casing removably secured to the yoke-shaped piece, a clutch connection between the shaft of the circulating pump and the commutator-shaft, a hub integral with the 10 pump-casing and adjacent the clutch for receiving the water-tight packing material, a packing-nut on the hub whereby when the casing is removed from the yoke-shaped piece the pump-shaft is disengaged from the commutator-shaft, and the packing-nut may be removed as described.
- 15 3. An improvement of the class described, an engine casing, a yoke-shaped piece having a hub portion removably mounted in the engine-casing, a commutator-shaft, a sleeve

encircling the commutator-shaft and located between said shaft and the yoke-shaped piece, means for securing the yoke-shaped piece and bushing to the casing, a circulating 20 pump-casing detachably secured to the arms of the yoke-shaped piece, a hub extending from the pump-casing towards the engine-casing, bushings carried by the pump-shaft and located between the same and the hub, a packing-nut on the inner end of the hub, a clutch connection between the commutator and the pump-shaft whereby when the pump-casing is removed from the yoke-shaped piece, the pump-shaft is disengaged from the commutator-shaft, and whereby any leakage from the pump is prevented from entering the crank-casing.

JAMES FRANK DURYEA.
